UNITED STATES PATENT OFFICE.

CORNELL FLAGSTAD AND OSCAR A. FLAGSTAD, OF MINNEAPOLIS, MINNESOTA.

COLLAPSIBLE CARRIER.

Application filed April 7, 1924. Serial No. 704,604.

To all whom it may concern:

Be it known that we, CORNELL FLAGSTAD and OSCAR A. FLAGSTAD, citizens of the United States, residing at Minneapolis, in the county of Hennepin and State of Minnesota, have invented certain new and useful Improvements in Collapsible Carriers, of which the following is a specification.

This invention relates to collapsible carriers, and the main object is to provide a practical, efficient and highly novel construction of collapsible crate, particularly adaptable for enclosing and shipping such objects as furniture, washing machines, ice boxes, sewing machines and other similar heavy devices; and in which, after the object has reached its destination, the crate may be collapsed into a comparatively small space and returned to the original shipper for use in again shipping other things, thus economizing on crating material by using a single crate a large number of times. Further and more specific objects will be disclosed in the course of the following specification, reference being had to the accompanying drawing, in which:

Fig. 1 is a perspective view of a crate embodying our invention.

Fig. 2 is an enlarged elevation of one of the crate ends as seen from the side, with portions broken away for purpose of illustration.

Fig. 3 is an enlarged detail section, as seen on the line 3—3 in Fig. 1.

Fig. 4 is a perspective detail of one of the securing members used in fastening an object in the crate.

Fig. 5 is an enlarged view of the securing device which is used to lock the crate in its compact or knocked-down position.

Fig. 6 is an enlarged detail sectional view on the line 6—6 in Fig. 5.

Referring to the drawing more particularly and by reference characters, A and B designate the side sections and C and D the end sections of a crate having a head or closing device E.

The side sections A and B are preferably of identical construction, and each consists of a pair of upright end members 7 and 8, horizontal members 9 and 10, side members 11 and 12, and a diagonal cross bar 13, all secured together, as by nails, so as to form a strong and rigid frame. The end sections each consist of a pair of crossed and rigidly connected members 14 having a transverse

cross bar 15 rigidly secured to their lower ends, and having a second cross bar 16 hingedly secured to their upper ends by hinges 17 having springs 18 adapted to normally hold the cross bar against the members 14.

The side sections are provided near their upper and lower corners with similarly constructed receiving members 19 and 20, having slots 21 adapted to receive the tongues 22 of latch members 23 and 24, which are also preferably of similar construction. The members 24 are locked into the members 20 by a tilting and sliding movement of the end section, C or D, to which they are attached, while the upper members 23 are locked into the members 19 by a similar tilting and sliding movement of the hinged cross member 16 to which they are attached. The members 23 and 24 are provided, above the tongues 22, with shoulders 25, which engage under the upper ends of the slots 21 to prevent retraction of the tongues after they are once secured in their vertical positions in the receiving members 19, 20. Thus when the four sections A, B, C and D are set up in interlocked positions they can only be released and separated by first tilting the members 16 outwardly.

The cover or head section E of the crate consists preferably of a pair of crossed slats 26 and 27, pivotally connected as at 28. The slat 26 is long enough to rest on the end or hinged members 16, and is provided at its ends with rigid angular fingers 29 adapted to engage over the members 16 to prevent them from being swung outwardly when the crate is closed. A plate or strap 30 may be secured upon the members 16 to receive said fingers 29. The slat 27 is shorter than the slat 26 and is adapted when swung transversely thereof, to engage with its ends under the members 9 of the side sections, and thus locks the head and consequently all the sections together in a complete crate.

It may be noticed that the crate is not provided with a detachable bottom section. Such a section might of course be provided and could be loosely supported by the members 10 or might be hinged to one of the side sections A or B, but loose and hinged bottoms are common and well known in the art, and are therefore not here illustrated, except unless the members 10 may be considered as a bottom. These members 10 are rigid portions of the side sections A and

B, and primarily support the washing machine, piece of furniture or other object placed in the crate. If such an object has any play within the crate so as to render it liable to escape through the open bottom, it is firmly secured within the crate, so as to be rigid therewith, by means of angle iron members 31 having perforated flanges 32, which are nailed in the crate adjacent to the object, as may be found necessary or desirable.

When the filled crate has reached its destination and is to be emptied, collapsed and returned, the operator first releases and removes the top section E by turning the bolt or locking slat 27. The members 16 are then turned down until the locking members 23 are released from the members 19. The end sections C and D are then swung outwardly and are completely released from the side sections by being raised until the locking members 24 are free. The side sections A and B are now free to be pulled away. The sections C, D and E (and also the bottom section if there be one) are now placed in one of the side sections and are retained therein by securing the other side section thereto. A convenient latch for thus securing the side sections thereto. A convenient latch for thus securing the side sections together is shown in Figs 1, 5 and 6, and consists in part of a bracket 33 having a projecting finger 34, and a bail 35 adapted to extend beyond the tongue. The interlocking member on the opposite side section consists of a bracket 36, having a socket 37 to receive the finger 34, and a slot 38 to receive the bail 35. A manually releasable spring retained latch 39 is slidably arranged in the member 36 and is adapted to detachably secure the bail 35 in the notch 38.

It is understood that suitable modifications may be made in the design and structural details of the crate herein illustrated and described, provided, however, that such modifications come within the spirit and scope of the appended claims.

Having now therefore fully shown and described our invention what we claim to be new and desire to protect by Letters Patent is:

1. In a crate, a pair of side sections, a pair of end sections adapted to be secured

at their lower corners to the ends of the side sections, securing members hingedly mounted on the upper ends of the end sections, means at the ends of said securing members for detachably engaging the side sections, and means for engaging said securing members to prevent the means at the ends thereof from swinging out of engagement with the side sections.

2. In a crate having a detachable end section, said section having means at one end thereof for detachably securing said end to the crate, the other end of the end section having a securing member hingedly secured thereto and extending transversely of the section for engagement with opposite sides of the crate, tongue members rigidly secured to said securing member for engagement with the crate, and means to lock said securing member against swinging movement to prevent the release of the tongue members.

3. In a collapsible crate having separable side, end and cover sections, means for detachably securing the lower ends of the side and end sections together, securing devices hingedly mounted at the upper ends of the end sections and for outward swinging movement therefrom for securing the upper ends of the sections to the side sections, means extending from the cover section to engage the securing devices, to prevent them from being released, and means for securing the cover section to the crate.

4. In a crate of the character described, a pair of side sections each consisting of a shallow frame, a pair of substantially flat end sections, each having locking members at its four corners for locking engagement with the adjacent corner portions of the side frames, the locking members at the upper corners of each end section being tiltable outwardly and spring-held with respect thereto for releasing movement from the side sections, a cover section for the crate, and means operative by securing the cover section to lock the upper locking members of the end sections.

In testimony whereof we affix our signatures.

CORNELL FLAGSTAD.
OSCAR A. FLAGSTAD.
